UNITED STATES PATENT OFFICE.

OLIVER C. CURTISS, OF PHILADELPHIA, PENNSYLVANIA.

DESIGN FOR A TOY SAVINGS-BANK.

56,912.

Specification for Design.

Patented Jan. 18, 1921.

Application filed August 6, 1920. Serial No. 401,785. Term of patent 14 years.

To all whom it may concern:

Be it known that I, OLIVER C. CURTISS, a citizen of the United States, residing at Philadelphia, in the county of Philadelphia and State of Pennsylvania, have invented a new, original, and ornamental Design for a Toy Savings-Bank, of which the following is a specification, reference being had to the accompanying drawing, forming a part thereof.

The figure is a perspective view of a toy savings bank, showing my new design.

I claim:

The ornamental design for a toy savings bank, as shown.

OLIVER C. CURTISS.
